UNITED STATES PATENT OFFICE

CHARLES HENRY WILD, OF BALTIMORE, MARYLAND, ASSIGNOR TO BURT MACHINE COMPANY, INC., A CORPORATION OF MARYLAND

CASE FILLING MACHINE

Application filed February 23, 1931. Serial No. 517,644.

This invention relates to a machine for filling cases or boxes with cans, cartons, bottles, or the like, and is of the general type of this class of machines disclosed in my United States Patent No. 1,443,157, issued January 23, 1923.

In the above enumerated patent issued to me, adjusting means are provided for accommodating varying sizes of articles to be packed. In this application improved means are provided for making adjustments for various parts of the machine to accommodate different size packages to be packed, the object being to simplify the manipulation and adjustment of the machine.

A further object of this invention is to provide an adjustable funnel, thus avoiding a change of the same as different sizes of containers are required.

20 A further object of my invention is the providing of means for simultaneously changing the various loading devices to accommodate different size cans or packages being packed, thus avoiding a rather slow 25 and tedious process of changing singly the various loading devices.

A further object of my invention is the providing of improved means for relatively spacing simultaneously the loading devices.

30 A further object of my invention is the providing of automatic means for adjusting the plunger head to accommodate the adjustment of the funnel.

With the foregoing and other objects in view, my invention consists of the novel construction, combination and arrangement of parts as hereinafter specifically described and illustrated in the accompanying drawings, wherein is shown the preferred embodiment of my invention; but it is understood that changes, variations and modifications can be resorted to which come within the scope of the claims hereunto appended.

In the drawings of the herein described embodiment of my invention, Figure 1 is a side view in elevation of the machine adjusted for the maximum size of containers or cases, and for the maximum size of cans or packages to be packed; Fig. 2 is a plan view of the machine shown in Fig. 1; Fig.

3 is an end view taken in end elevation looking in the direction of the arrow 3, in Figs. 1 and 2; Fig. 4 is a view, partly in section, in elevation similar to the view shown in Fig. 3, but taken through section 4—4 of 55 Figs. 1 and 2; Fig. 5 is an enlarged view in elevation of the portion of the main housing guide 37 carrying the markings to accommodate the adjustment of supporting member 38; Fig. 6 is an enlarged view of the end of 60 loading floor 32, showing particularly the connection of fulcrumed runway members 47 on the respective sides of the machine, Fig. 7 being a side view in elevation of that shown in Fig. 6; loading floor 31 is similarly connected to fulcrum runway members 46.

Similar numerals refer to similar parts throughout the several views.

1 is the bottom rail; there are two shown, one on each side of the machine, and form the 70 base of the machine. 2 are the legs which are secured to bottom rail 1, said legs being extensibly adjustable in order that the machine may have the desired angle with reference to the horizontal, and concerning which 75 I claim nothing in this application. 3 is a header, slidably mounted on bottom rail 1 and adjusted in position thereon to suit the size of container to be filled and as determined by pin 4 inserted through hole 5 in 80 header 3 and into holes 6 in bottom rail 1; header 3, after being adjusted, is secured to bottom rails 1 by dog 7 and clamping screw 8, whereby bottom rails 1 are clamped between dog 7 and header 3 upon the setting up 85 of clamping screw 8.

In header 3 are supporting members 9, 10 and 11 operating on one side over guide 12 formed on header 3, and on the other side by means of support 13 and nuts 14 and 15 90 formed thereon, and are supported thereby and in which support 13 screw 16 is secured and in which nuts 14 and 15 screws 17 and 18 operate, the latter screws being formed integral with the shaft 19, which shaft is 95 journaled at the bottom into lug 31 on header 3. In the lower end of shaft 19 is a hole which is threaded and in which screw 16 operates, and at the top shaft 19 is journaled in bearing 21 in header 3, and its weight is taken 100

by collar 22 which is secured to shaft 19 by pin 23. On each of supporting members 9 and 10 are secured butting end members 25 and 26, end butting member 24 being permanently secured to header 3. These members operate against guide 11 on the opposite side from supporting members 8 and 9, as mentioned above.

28 is the funnel side spacing member secured to header 3, and has integral therewith funnel bottom member 29. 30, 31 and 32 are loading floors upon which cans, if cans are being packed, roll prior to packing. These floors are inserted under end butting members 24, 25 and 26. End member 33 has secured to it and carries top funnel arm 27, and is itself secured to supporting member 11.

Loading floor 30 is secured to header 3; loading floors 31 and 32 rest on supporting members 9 and 10 and are carried thereby. These floors are provided with flanges on the rear and are brought to sharp edges on the front edge, or edge nearest the container. End butting members are also brought to a sharp edge on the front and are in alignment with side spacing member 28.

34 is the funnel side spacing member to which is attached funnel bottom member 35. These two members are relatively stationary and are secured to main housing 36. In main housing 36 is guide 37 in which operates supporting member 38; this member having a slot therein 39 for adjustment purposes and is secured in said guide by bolt 40. Supporting member 38 is attached thereto and carries top case guide 41, this arm being adjustable vertically to accommodate the adjustment of top case guide 27 to accommodate the height of containers to be used.

40 Main housing guide 37 is provided with suitable markings on its face, and a pointer 42 is secured to supporting member 38 to indicate the size of the container used. Likewise, end member 33 has a mark registering with markings on header 3, shown as markings 43.

On bottom rails 1 is secured a sorting head 44 to which is secured bottom runway 45. This is the base floor from which the others are adjusted. 46 and 47 are fulcrumed runway members fulcrumed into sorting head 44 on one end and carried by links 48 and 49 at the other end. These runways and links are substantially alike on both sides of the machine, the runway consisting of carriers 50 and 51 being secured to runway members 46 and 47, respectively.

52 is hand adjusting lever fulcrumed to main housing 36 at 53, and has fulcrumed to it links 48 and 49 at 54 and 55, respectively; the other end of said links being pivotally connected to fulcrumed runway members 46 and 47, respectively, and positioned so that upon the operation of said lever 52 the respective desired spacings may be had between the

respective loading floors 30, 31 and 32. Loading floors 31 and 32 are carried by runway members 46 and 47, respectively, on one side, the side nearest the funnel, by being inserted within said members as shown at 56 and 57. (See Fig. 6.) Links 49 are extended downward and operate against bottom rail 1, and are provided with pin 58 going through the same and resting on top of bottom rail 1 when in adjusted position, said links being provided with a series of holes for this adjustment, said pin being provided with a head to lock over bottom rail 1 to prevent its withdrawal by the jarring of the machine in operation.

Between bottom runway 45 and carriers 50 and 51 are stop appliances 59 and 60 and 61 for stopping the supply of cans when the plunger is operating to fill the container; appliances 60 and 61 being fulcrumed at 66 and 67, respectively, on fulcrum runway members 46 and 47, respectively. These members are tilting members and are operated by link 68 having a relative longitudinal movement caused by the operating device 69 pulling same up or down by mechanism not shown, link 68 being mounted on links 70 and 71. The adjustment of various floors being had through slots 72 and 73 in said links. Two of these stop appliances, 60 and 61, however, are carried for means of adjustment by fulcrumed runway members 46 and 47.

62 are the plunger rods carrying adjustable plunger heads 63 and operate transversely to the feeding of the articles on the loading floors 30, 31 and 32 for pushing the same therefrom into the container. In plunger head 63 is telescoped adjustable extensions 64 held out in maximum position by springs 65, these extensions butting against end butting members 24, 25 and 26, and accommodate themselves to adjustment of header 3 on bottom rail 1. As I claim nothing concerning the mechanism for operating the plunger as such, I will not further describe the same; the adjustable head, however, being a feature of this invention.

In sorting head 44 is adjusting member 74 operating at one end by a sliding fulcrum 75 in sorting head 44 in slots 76 and held in position by pin 77 operating through holes 78 in adjusting member 74, and in holes 79 in sorting member 44, there being a number of such holes for adjustment. This permits said adjusting member to be tilted to accommodate the various size cans to enter between adjusting member 74 and stop members 80 fixed on fulcrum member 47.

81 is the container carrier adjustable with reference to bottom rail 1 by means of bracket 82, against which it is secured and adjustable therewith by means of slot 83 and bolt 84.

The operation of my invention is as follows:

The size of the container being determined

- upon, header 3 is adjusted on bottom rail 1 to fit funnel side spacing member 28 and funnel side spacing member 34 within the container reasonably snug. Bottom funnel members 29 and 35 being within the container on the bottom, top funnel arms 27 and 41 are then raised as follows: Top funnel arm 27 is raised by means of revolving shaft 19 by means of pin 23, whereby screw 18 raises nut 15. Top funnel member 41 is raised by slackening bolt 40 and raising supporting member 38 until the top funnel arms 41 and 27 correspond in height and fit within the container when in position. Hand adjusting lever 52 adjusts loading floors 31 and 32 with reference to loading floor 30 and with reference to each other, according to the size case to be packed, determined by the openings or holes in link 49 held in place by pin 58.
- Adjusting member 74 is adjusted to permit the correct size case to pass between it and stop 80. The adjustable plunger head and adjustable plunger extension 63 and 64 take care of the varying size of the container caused by the adjustments of header 3.
- In these specifications and claims, when I use the term, "packages, cans, or articles to be packed", I mean such articles as by their nature are adapted to being packed by this machine, such as, round cans, round bottles, round cartons, or any other round article.
- Having thus described my invention, what I claim and desire to secure by Letters Patent is:
1. In a machine for filling cases with cans or other packages having feeding means consisting of tracks spaced apart in a substantially vertical direction, and a plunger reciprocating on a path transverse to the feed the plunger carrying an automatically adjustable head, said adjustable head comprising extension members and means to automatically adjust the extreme scope thereof and maintain said adjustment between fixed limits to accommodate varying size containers.
2. In a machine for filling cases, a plurality of loading floors spaced apart in a substantially vertical direction to receive goods to be fed into a container and means for relatively adjusting said floors at one end simultaneously.
3. In a machine for filling cases, a plurality of loading floors spaced apart in a substantially vertical direction to receive goods to be fed into a container and means for relatively adjusting said floors at one end simultaneously consisting of a plurality of screens operating in a plurality of nuts secured respectively to the various floors, the pitch of the respective screws being such that the relative spacing is obtained simultaneously by synchronous operating of the various screws and nuts relatively.
4. In a machine for filling cases provided with a plurality of loading floors spaced apart in a substantially vertical direction and provided with end butting members to limit the supply of the article to be loaded as fed on to said floors, means for adjusting said end butting members longitudinally with reference to said floors to regulate the number of articles to be fed in a row into the container, and means for simultaneously and automatically therewith adjusting a funnel side spacing member which determines the size of the funnel in a longitudinal direction to enter a case.
5. In a machine for filling cases provided with a plurality of loading floors spaced apart in a substantially vertical direction and provided with end butting members to limit the supply of the article to be loaded as fed onto said floors, means for adjusting said end butting members longitudinally with reference to said floors to regulate the number of articles to be fed in a row into the container, and means for simultaneously and automatically therewith adjusting a funnel side spacing member which determines the size of the funnel in a longitudinal direction to enter a case consisting of a header to which said funnel side spacing member is attached and to which said end butting members are attached, and provided with means for securing said header in a longitudinal adjusted position.
6. In a machine for filling cases provided with a plurality of loading floors spaced apart in a substantially vertical direction and provided with end butting members to limit the supply of the article to be loaded as fed on to said floors, means for adjusting said end butting members longitudinally with reference to said floors to regulate the number of articles to be fed in a row into the container consisting of a header supporting the several floors and through which the said floors operate and to which the said end butting members are secured, the same being provided with means for securing the same in a fixed longitudinal direction after said adjustment, and means provided in said header for simultaneously adjusting the relative position of said loading floors with reference to each other.
7. In a machine for filling cases provided with a reciprocating plunger, and a plurality of loading floors spaced apart to accommodate packages to be fed and situated whereby packages thereon may be pushed therefrom by said plunger, means for directing said packages on to the respective loading floors and a stop appliance between said directing means and said floors to stop the feeding of said packages when the floors are filled to capacity, means for simultaneously changing the spacing between said floors at one end of said directing means and said stop appliances to accommodate different size packages.

8. In a machine for filling cases provided with a reciprocating plunger, and a plurality of loading floors spaced apart to accommodate packages to be fed and situated whereby packages thereon may be pushed therefrom by said plunger, means for directing said packages on to the respective loading floors and a stop appliance between said directing means and said floors to stop the feeding of said packages when the floors are filled to capacity, means for simultaneously changing the spacing between said floors at one end of said directing means and said stop appliances to accommodate different size packages
- 10 15 20 25 30 35 40 45 50 55 60 65 70 75 80 85 90 95 100 105 110 115 120 125
8. In a machine for filling cases provided with a reciprocating plunger, and a plurality of loading floors spaced apart to accommodate packages to be fed and situated whereby packages thereon may be pushed therefrom by said plunger, means for directing said packages on to the respective loading floors and a stop appliance between said directing means and said floors to stop the feeding of said packages when the floors are filled to capacity, means for simultaneously changing the spacing between said floors at one end of said directing means and said stop appliances to accommodate different size packages, said stop appliances being carried by the adjusting mechanism and jointly connected to an operating means and a variable connection connecting said stop appliances to said operating means whereby the said stop appliances may be positively operated in various desired vertically adjusted positions.
10. In a machine for filling cases provided with a reciprocating plunger, and a plurality of loading floors spaced apart to accommodate packages to be fed and situated whereby packages thereon may be pushed therefrom by said plunger, means for directing said packages on to the respective loading floors, and a stop appliance between said directing means and said floors to stop the feeding of said packages when the floors are filled to capacity, means for simultaneously changing the spacing between said floors at one end of said directing means and said stop appliances to accommodate different size packages, said directing means being provided with an adjusting member and a stop, an adjusting member comprising a movable runway provided with a sliding fulcrum in said directing means and an adjusting means at the other end thereof whereby the same may be tilted and moved to change the spacing between it and stop means in said directing means to accommodate the lower loading floors.
11. In a machine for filling cases pro-
- vided with a plurality of loading floors spaced apart in a substantially vertical direction to receive goods to be fed into a container and means for relatively adjusting said floors, a case guide to control the entry of the goods into the container and means for controlling the vertical height of said case guide to accommodate the container.
12. In a machine for filling cases provided with a plurality of loading floors spaced apart in a substantially vertical direction to receive goods to be fed into a container and means for relatively adjusting said floors, a funnel to control the entry of the goods into the container and means for adjusting the vertical height of said funnel to accommodate the container, consisting of top funnel arms secured to members and means for simultaneously operating said members as loading floors are being adjusted.
13. In a machine for filling cases, a plurality of loading floors spaced apart in a substantially vertical direction to receive goods to be fed into a case, a funnel through which said goods may be fed into said case and means for relatively adjusting said floors and the substantially vertical height of said funnel at one end simultaneously.
14. In a machine for filling cases a plurality of loading floors spaced apart in a substantially vertical direction to receive goods to be fed into a case, and means for adjusting said floors at one end simultaneously consisting of a plurality of levers operating as a single unit, said levers being connected to the ends of said floors respectively, whereby by the operation of said levers the floors are simultaneously spaced with reference to each other.
15. In a machine a plurality of loading floors superimposed, a case guide adjusted with reference to said loading floors whereby goods on said floors may be forced through said case guide into a container adjacent to said case guide, means for forcing said goods into said container, a funnel and means for adjusting one side of said funnel to fit said container.
16. In a machine a plurality of loading floors superimposed, a funnel adjusted with reference to said loading floors whereby goods on said floors may be forced through said funnel into a container adjacent to said funnel, means for forcing said goods into said container, means for adjusting the size of said funnel to fit said container, and means for adjusting the said funnel longitudinally simultaneously with the longitudinal adjustment of said floors.
17. In a machine a plurality of loading floors superimposed, a funnel adjusted with reference to said loading floors whereby goods on said floors may be forced through said funnel into a container adjacent to said

funnel, means for forcing said goods into said container, means for adjusting the size of said funnel to fit said container, and means for adjusting the said funnel vertically and the respective loading floors simultaneously to accommodate different sized cans to be packed.
